INFLATING PUMP OR SIMILAR ARTICLE

Stanley Barnett, Mount Vernon, N.Y.
(490 Nepperhan Ave., Yonkers, N.Y. 10701)

Filed Feb. 9, 1971, Ser. No. 114,096

Term of patent 14 years

Int. Cl. D23—01

U.S. Cl. D23—14

FIG. 1 is a top plan view of an inflating pump or similar article showing my new design;

FIG. 2 is a bottom plan view thereof;

FIG. 3 is a side elevational view thereof;

FIG. 4 is a front elevational view thereof; and

FIG. 5 is a side elevational view thereof, showing the side opposite that seen in FIG. 3.

The flexible tube has been shown in a bent position in FIGS. 3 and 5 for convenience of illustration.

I claim:

The ornamental design for an inflating pump or similar article, substantially as shown and described.
